Des. 234,033

Patented Jan. 7, 1975

234,033

RACING CAR SEAT

Kenneth D. Tarbet, 298 E. Bellevue,
Atwater, Calif. 95301

Filed Mar. 7, 1973, Ser. No. 338,653

Term of patent 14 years

Int. Cl. D6—01

U.S. Cl. D6—48

FIG. 1.

FIG. 2.

FIG. 3.

FIG. 4.

FIG. 5.

FIG. 6.

FIG. 7.

FIG. 1 is a front elevational view of the racing car seat showing my new design.

FIG. 2 is a rear elevational view thereof.

FIG. 3 is a side elevation thereof, as seen from the right side of the seat.

FIG. 4 is a side elevation thereof, as seen from the left side of the seat.

FIG. 5 is a top plan view of the seat.

FIG. 6 is a bottom view of the seat.

FIG. 7 is a perspective view of the seat.

I claim:

The ornamental design for a racing car seat, as shown.
